ICE BUCKET

Jules P. Gits, River Forest, Ill., assignor of one-half to
Joseph A. Gits, River Forest, Ill.

Application December 24, 1956, Serial No. 44,319

Term of patent 14 years

(Cl. D58—17)

FIG. 1.

FIG. 3

FIG. 2.

Fig. 1 is a front elevational view of an ice bucket showing the handle inclined to the horizontal,

Fig. 2 is a plan view of the ice bucket showing the handle horizontal, and

Fig. 3 is an enlarged fragmentary view taken from the left of Fig. 1.

The characteristic features of my design for the ice bucket disclosed reside in the ornamentation appearing on the side of the body portion of the ice bucket as shown.

I claim:

The ornamental design for an ice bucket, as shown and described.
